STRIKER TOOL

Walter J. Blue and Stanley F. Blue, Cleveland, Ohio

Application February 9, 1955, Serial No. 487,160

1 Claim. (Cl. 72—138)

2

The present invention relates generally as indicated to a striker tool, and more particularly to such tool which is adapted for wearing on the thumb or other finger for conveniently striking the horizontal and vertical joints during erection of masonry walls.

It is the present practice in the masonry art to employ a bar-like striker tool or a tuck pointing trowel which must be alternately set aside after use and then picked up after additional courses of blocks or bricks have been laid. Likewise, the brick-layer usually sets aside his trowel or other tool in order to have a free hand for manipulation of the striker tool.

It is one principal object of this invention to provide a striker tool which may be constantly worn on the mason's or bricklayer's thumb without interfering with the normal use of the trowel and without requiring setting aside of the trowel, because the handle of the latter may yet be gripped by the remaining four fingers of the same hand. Moreover, the mason, if he so desires, may use his thumb with the present striker tool thereon to assist in the gripping of the trowel whereby said tool, in effect constitutes a false thumb or an extension thereof.

Other objects and advantages of the present invention will become apparent as the following description proceeds.

To the accomplishment of the foregoing and related ends, the invention, then, comprises the features herein-after fully described and particularly pointed out in the claims, the following description and the annexed drawings setting forth in detail a certain illustrative embodiment of the invention, this being indicative, however, of but one of a few of the various ways in which the principle of the invention may be employed.

In said annexed drawings:

Fig. 1 is a top plan view of the present striker tool;

Fig. 2 is an end elevation view of the tool as viewed upwardly from the lower end of Fig. 1; and

Fig. 3 is a side elevation view of the tool as viewed from the righthand side of Fig. 1.

Referring now more particularly to the drawings, the tool herein comprises a generally oval or elliptical body 1 having a recess 2 therein open at one end for insertion of the thumb therewith, the recess 2 preferably being of generally oval or elliptical cross-section to conform to the normal transverse cross-section shape of the thumb, and preferably the closed end 3 of recess 2 is of generally semi-ellipsoidal form to provide a comfortable stop for the tip of the thumb.

By shaping the recess 2 as shown, the tool body 1 is non-rotatable on the thumb. In order to snugly retain the body 1 on the thumb, the open end of recess 2 thereof has secured thereto an elastic band or cuff-like member 4 which is adapted to snugly embrace the thumb in an area between the first and second joints.

Said cuff-like portion 4 of the tool may be of gathered fabric having an elastic element therein, or it may be of corrugated elastic material, or it may be of woven fabric comparable to that usually employed on the cuffs of gloves,

sweaters, or the like. Obviously, the function of this elastic portion 4 of the tool is simply to snugly engage the thumb so that the tool will not drop therefrom during normal use. Therefore, insofar as the present invention is concerned, the body 1 of the tool may be secured to the thumb by draw strings or the like instead of the cuff shown herein. In fact, the body 1 of the tool may, if desired, be secured over, or substituted for, the thumb of a glove or mitten.

10 The body 1 of the tool is preferably made of a hard-wear-resisting material such as steel, but it may as well be of some other material including rigid or flexible plastics, wood, or any comparable material. Accordingly, the manner of securing the cuff 4 to the body 1 of the tool will depend somewhat on the particular material from which the tool body is made; that is, if plastic material were employed as the body material, the cuff may be cemented thereto. On the other hand, if the tool body 1 were made of metal, it may be preferred to rivet the cuff 4 thereto or else to secure the same by other means such as, for example, forming a groove in the periphery of the tool adjacent the open end thereof and employing a band or wire which grips the cuff in such groove.

The closed or working end of the tool body 1 comprises, 25 when it is desired to provide rounded, inset mortar joints with a correspondingly rounded, axially projecting rib 5 which extends transversely across the major transverse axis of the tool body 1 and which is preferably transversely coextensive with the body 1. Thus, horizontal joints may be conveniently struck simply by moving the thumb horizontally in either direction with the thumb nail facing upwardly and, if desired, the tool may be moved horizontally with the longitudinal axis of the tool body 1. The thumb may be obliquely disposed with respect to the surface of the wall under construction rather than perpendicular to such surface.

In addition to the aforesaid rib or projection 5, there is another rib 6 which, as shown, is normal to rib 5 and which extends across the minor transverse axis of said body 1 and radially therewith. Said rib 6 extends longitudinally of body 1 and terminates short of the end of rib 5, whereby the end surfaces 7 of rib 6 serve as stops or guides to determine the depth of striking of the joints when the rib 5 is used as on the horizontal joints.

45 Either side of said cross rib 6 may conveniently be used for striking vertical mortar joints simply by moving the hand in a vertical plane up or down with the thumb nail facing upwardly and inclined either downwardly toward the wall surface or downwardly away from wall surface so that the mason has the option of working from the bottom up or from the top down in the vertical joints.

In the case of the rib 6 aforesaid, full depth of striking out of mortar therewith is achieved by having the longitudinal axis of the tool body 1 disposed substantially in 55 a vertical position so that the side portions 8 of the other rib 5 which project transversely serve as depth guides; and, of course, the depth of striking with rib 6 will become progressively less as the tool body longitudinal axis is tilted away from the wall.

60 It will be apparent that the rib 5 alone may be employed in striking out the mortar from both horizontal and vertical joints simply by turning the hand so that the opposite sides of the thumb face respectively upward and downward, and this is a preferred manner of use of the tool herein, since in both instances, that is, in the striking of horizontal and vertical joints, the thumb is moved in a horizontal and vertical plane and may be perpendicularly or obliquely disposed with respect to the line of the joint without noticeably affecting the depth and shape of 65 the joint recessed thereby.

As evident, the thickness of ribs 5 and 6 will be the same or less than the thickness of the mortar joint so that

the rib ends may enter the joint to the desired extent. Straight inset joints may be formed by using a tool in which the rib 5 has a plane end intersecting the side portions 8 in sharp or only slightly rounded external corners.

Other modes of applying the principle of the invention may be employed, change being made as regards the details described, provided the features stated in the following claim, or the equivalent of such, be employed.

We therefore particularly point out and distinctly claim as our invention:

A striker tool for masonry joints comprising a body formed with a thumb-receiving recess in one end of generally elliptical cross-section shape conforming approximately to the cross-section shape and size of a person's thumb, with diametrically opposed axial ribs above and below the minor axis of such recess terminating in end shoulder surfaces at the other end of said body, and with a transverse rib whose axis coincides with the major axis

of such recess, said transverse rib projecting beyond the shoulder surfaces and having an outer surface adapted to point a horizontal mortar joint to a depth determined by the shoulder surfaces upon movement of the thumb laterally, said axial ribs adapted to point vertical mortar joints to a depth determined by the height of said axial ribs from the respective sides of said transverse rib upon vertical movement of the thumb.
